UNITED STATES PATENT OFFICE.

WILLIAM MEIER, OF NEW YORK, N. Y.

MIXING FAUCET.

1,402,633.

Specification of Letters Patent. Patented Jan. 3, 1922.

Application filed July 2, 1920. Serial No. 393,632.

To all whom it may concern:

Be it known that I, WILLIAM MEIER, a citizen of the United States, and a resident of the city of New York, borough of Manhattan, in the county and State of New York, have invented a new and Improved Mixing Faucet, of which the following is a full, clear, and exact description.

This invention relates to liquid mixing means, and has reference more particularly to means for mixing hot and cold water, said means being controlled by a hand lever so that the water issues from the faucet at the desired temperature. This application further relates to and is an improvement over the device for which application was filed by me June 19, 1919, Serial Number 305269, and is also an improvement over the device shown in application filed October 25, 1919, Serial Number 333151.

An object of this invention is to provide a hand controlled mixing faucet in which the flow and temperature of the water issuing from the faucet can be accurately controlled by a lever.

Another object of this invention is to provide a mixing faucet which can be easily disassembled so that repairs can be made.

A further object of this invention is to provide a mixing faucet which has valves of resilient material, said valves being provided with means for adjustment when necessary due to wear.

A still further object of this invention is to provide a mixing faucet which is especially adapted for use on sinks, shower baths, and the like.

Reference is to be had to the accompanying drawings forming a part of this specification, in which it is understood that the drawings illustrate only one form of the invention, and in which—

Figure 1 is an elevation of the mixing faucet with parts broken away to disclose the construction.

Figure 2 is a sectional plan view of the mixing faucet being taken on the line 2—2 of Figure 1.

Figure 3 is a fragmentary sectional view of one of the improved adjustable valves.

Figure 4 is a plan view of the faucet.

Figure 5 is an elevation of a faucet modified for use on a shower bath.

Referring to the accompanying drawings

by numerals, 10 indicates a mixing chamber 55 which is preferably cylindrical in shape, said chamber being provided with a base 11, said base being provided with an outlet pipe 11_a adapted to permit the egress of mixed liquids, such as hot and cold water, from 60 said chamber. The upper end of the chamber 10 is threaded to receive a screw cap 12 which is also provided with a stuffing box 13. The stuffing box 13 slidably engages a control rod 14 so that said rod is positioned 65 coaxial with the chamber 10. An annular shoulder 15 is provided on the rod 14 which is adapted to engage an annular recess in the cap 12 so that axial movement of the rod 14 is prevented. A lever 16 is secured to the 70 upper end of the rod 14 by means of pin 17 so that said rod may be rotated by said lever. A pair of outstanding lugs 18 are formed diametrically opposite on each side of the inside surface of the chamber 10 adjacent 75 the cap 12, and a cam block 19 is pivotally suspended between one pair of lugs 18 by means of a pin 20 while a cam block 21 is similarly suspended between the other pair of lugs 18 by means of a pin 22.

Cam slots are formed in each of the blocks 19 and 21, the block 19 being provided with a cam slot 23 which is substantially arcuate in shape, while the block 21 is provided with a cam slot 24 which has a substantially vertical straight section 25, an upper arcuate section 26, and a lower arcuate section 27, sections 26 and 27 being turned in opposite directions. A collar 28 is provided with internal screw threads which engage screw 90 threads 29 on the lower end of the rod 14, so that as said rod 14 is rotated by means of the lever 16, the collar 28 will be moved axially along said rod. The collar 28 is provided with diametrically opposite outstanding 95 flanges 30, and a laterally extending pin 31 is secured to the end of one of the flanges 30 so as to engage the cam slot 23, and a laterally extending pin 32 is secured to the end of the other flange 30 so as to engage the 100 cam slot 24. The pins 31 and 32 serve to move the cam blocks 19 and 21 about their pivots when the collar 28 is moved vertically as the rod 14 is rotated. An inlet port 33 is provided in the wall of the chamber 10 adjacent the cam block 19, and an inlet port 34 is formed in the wall of said chamber 105 diametrically opposite the port 33 and adjacent

- the cam block 21. Each of the ports 33 and 34 has a threaded section 35 to which is secured water pipes 36 and 37 which may be curved, straight, or provided with unions 38 connecting said pipes to service pipes 39, passing through the wall 40 of the sink, the axis of said service pipes 39 being preferably at right angles to the axis of the pipe 11_a so that the water or other liquid is directed downwardly. The pipe 37 may supply cold water and the pipe 36 hot water, or vice versa.
- A valve stem 41 is pivoted at one end to the lower end of the block 19 by means of a pin 42, and a valve stem 43 is pivoted to the lower end of the cam block 21 by a pin 44. Each of the valve stems 41 and 43 is provided with a threaded section 45 which forms shoulders 46 with the valve stems 41 and 43. Frusto-conical resilient valve washers 47 and 48 are mounted coaxially on sections 45, the smaller ends of said washer being adapted to engage valve seats 50 formed on each of the ports 33 and 34 when the valve is in a closed position. Each of the washers 47 and 48 is preferably made of a soft material such as rubber and is held in place by a semi-spherical metal washer 51 held in place by a nut 52. The contact surface 53 of each of the washers 47 and 48 with the valve seats 50 is preferably semi-spherical in shape so that as the valve washers become worn they may be adjusted by tightening nuts 52 so that the surfaces 53 are flattened out and approach their respective valve seats more closely.
- In the modification shown in Figure 5, the outlet pipe 11_b may be formed on the wall of the chamber 10 and may be connected to a pipe 54 which leads to a shower bath or any other desired device.
- In operation, when the lever 16 is in the extreme position shown in Figure 4, the pins 31 and 32 will engage the cam slots 23 and 24 so that the cam blocks 19 and 21, pull the valve washers tightly against the valve seats 50 so that no water flows into the mixing chamber 10 through the pipes 36 and 37. As the lever 16 is slowly rotated in a clock wise direction, the collar 28 moves downwardly, thus causing the pin 32 to loosen but not unseat the valve washer 48 while the pin 31 opens the valve 47. At the position shown in Figure 1, valve 47 is fully opened and the valve 48 is still closed, and upon a continued clock wise rotation of the lever 16, the valve 47 will slowly close while the valve 48 opens until the proper temperature and flow of water from the pipe 11_a is obtained. Thus a thorough mixing of hot and cold water from the pipes 36 and 37 is obtained in the chamber 10.
- I would state in conclusion that while the illustrated example constitutes a practical embodiment of my invention, I do not limit

myself strictly to the mechanical details herein illustrated, since manifestly the same can be considerably varied without departure from the spirit of the invention as defined in the appended claims.

Having thus described my invention, I claim as new and desire to secure by Letters Patent:

1. In a faucet for mixing liquids, a mixing chamber, a plurality of liquid inlets associated with said chamber, a control rod rotatably associated with said chamber, a valve associated with each inlet, cam elements associated with each valve, a screw element associated with said rod and with said cam elements adapted to move axially of said rod when said rod is rotated, said axial movement being adapted to cause said cam elements to open or close said valves so that the flow of liquid into said mixing chamber will be controlled, means for rotating said rod, and means for permitting the egress of the mixed liquids from said chamber.
2. In a faucet for mixing liquids, a mixing chamber, a plurality of liquid inlets associated with said chamber, a control rod rotatably associated with said chamber, a valve associated with each inlet, pivotally mounted cam elements associated with each valve, a screw element associated with said rod and with said cam elements adapted to move axially of said rod when said rod is rotated, said axial movement being adapted to cause said cam elements to open or close said valves so that the flow of liquid into said mixing chamber will be controlled, means for rotating said rod, and means for permitting the egress of the mixed liquids from said chamber.
3. In a faucet for mixing liquids, a mixing chamber, a plurality of liquid inlets associated with said chamber, a control rod rotatably associated with said chamber, a valve associated with each inlet, a cam block pivotally mounted to the inside of said chamber adjacent each valve, a cam slot in each cam block, connecting means between said valves and cam blocks, screw means associated with said control rod and engaging said cam slots adapted to move said cam blocks about their pivots as said control rod is rotated, so that variable quantities of the several liquids are admitted through said inlets to said mixing chamber, means for rotating said rod, and means for permitting the egress of the mixed liquids from said chamber.

4. A device as described in claim 3, characterized by means for adjusting said valves relative to said valve inlets to allow for wear on said valves.

5. In a faucet for mixing liquids, a mixing chamber, a plurality of liquid inlets located in said chamber, a control rod rota-

tably associated with said chamber, a valve of resilient material disposed adjacent each inlet, a plate pivoted in the chamber adjacent each inlet, each plate having a cam slot 5 therein, connections between each plate and its adjacent valve, a spiral cam rib on the rotatable rod, a sleeve embracing said rod

and co-operating with said rib, and oppositely disposed connections extending from said sleeve and co-operating with the slots 10 of the pivoted plates whereby movement of the rod will be communicated through the sleeve to the plates and the valves.

WILLIAM MEIER.
